Filed Jan. 24, 1963, Ser. No. 73,293

Term of patent 14 years

(Cl. D49—1)

Fig.2

Fig.3

FIGURE 1 is a perspective view of a laundry lifter showing my new design;

FIGURE 2 is a side elevational view thereof;

FIGURE 3 is a plan view thereof.

The webbed portions of the lifter are plane, coextensive with the lower surface and coplanar with the side rib portions, as indicated in FIG. 1. The lower surface of the handle shaft is plane, except for the short rib adjacent the handle grip as indicated in FIG. 2.

I claim:

The ornamental design for a laundry lifter, substantially as shown.
